UNITED STATES PATENT OFFICE.

ALLAN W. WOODRUFF, OF CHICAGO, ILLINOIS.

FIREARM.

1,284,020.

Specification of Letters Patent.

Patented Nov. 5, 1918.

Application filed January 31, 1918. Serial No. 214,646.

To all whom it may concern:

Be it known that I, ALLAN W. WOODRUFF, a citizen of the United States, residing at Chicago, in the county of Cook and State of Illinois, have invented new and useful Improvements in Firearms, of which the following is a specification.

This invention while primarily intended for application to single-barrel shot-guns, yet, as will hereinafter appear, the mechanism is applicable, with but slight modification, to rifles, double barreled and magazine-guns, so that I am not to be understood as being limited in this respect.

The principal objects of my invention are to simplify and reduce the number of parts usually employed in gun mechanisms, and thereby materially reduce the cost of manufacture; to obviate the necessity of employing numerous small parts that are given to wear and breakage, whereby the upkeep is negligible; and finally, to so construct a gun that it is always "safe" except at the moment of firing, thereby rendering accidents less liable and also greatly increasing the life of the main-spring by placing the same under tension only at such times as the gun is ready for discharge.

Other objects and advantages of the invention will hereinafter appear, and the novel features of the same will be particularly described and pointed out in the claims.

Referring to the drawings:

Figure 1 is a central longitudinal sectional view, with parts in side elevation, of a firearm embodying my invention, the parts being shown in the position they occupy when normal and the gun is "safe";

Figs. 2 and 3 are similar views to Fig. 1, Fig. 2 showing the parts in the position they occupy when the gun is cocked and ready to fire, while Fig. 3 show the parts in the position they occupy after firing;

Fig. 4 is a bottom view of the gun;

Fig. 5 is a detail in perspective of the bottom cover-plate;

Fig. 6 is a detail in rear end elevation of the receiver or frame;

Figs. 7 and 8 are side and end elevations, respectively, of the top locking-bolt;

Figs. 9 and 10 are details in front end and side elevations, respectively, of the top cover-plate;

Fig. 11 is a detail in perspective, and enlarged, of the cocking-bar;

Fig. 12 is a detail in perspective of the cocking-bar actuating link;

Fig. 13 is a vertical transverse sectional view through the trigger, bottom cover-plate, and cocking-plate the section being taken at the point of connection of these parts.

Similar numerals of reference indicate similar parts in all the figures of the drawings.

It will be understood that the barrel 1, and the forearm 2, are of the conventional style and constitute no part of my present invention. The barrel is preferably formed with the top rib-extension 3, terminating in this instance in the usual "doll-head." The rear end of the extension is provided with a shallow cavity 4, for engagement with the top-locking bolt hereinafter referred to. The stock 5 has its grip 6 longitudinally recessed, as at 7, to receive certain parts of the lock-mechanism and is joined to the receiver or frame in the usual manner.

For convenience and strength, the receiver or frame is formed of a single casting, the upper part of the rear face of which is provided with a socket 8, into which fits a tenon 9, formed at the forward end of the top cover-plate 10, (see Figs. 9 and 10,) that closes the upper side of the recess 7 of the stock. The rear end of this top cover-plate extends beyond the end of the recess 7 of the stock and may be perforated to receive a screw 11, which passes therethrough and into the stock. By removing the screw it will be evident that the cover-plate may then be withdrawn rearwardly from its engagement with the receiver or frame and thus access may be obtained to the lock-mechanism within.

In advance of the tenon 9 of the cover-plate, the receiver or frame is provided near its upper side with a longitudinal bore 12, which latter near its front end is reduced as at 13, the two bores being in line with the shallow locking cavity 4 of the extension-rib of the barrel. These bores are further continued in the upper side of the tenon 9 of the cover-plate, said tenon being bored, as at 14, for the purpose. The groove 14 is not so deep as is the groove 12 with which it communicates, so that the front end of the tenon 9 forms a shoulder 15.

In the groove 14 and the bores 12 and 13 is mounted for reciprocation to a limited ex-

- tent the top locking-bolt 16, (see Figs. 7 and 8,) the front end of which bolt is reduced, as at 17, to correspond to the reduced bore 13, beyond the front end of which bore 5 said bolt slightly projects, is beveled, and is adapted to engage the cavity 4 of the barrel extension when the latter is closed, whereby the said barrel becomes locked against opening.
- 10 Between its middle and rear end, the locking-bolt is reduced, as at 18, such reduced portion forming a front shoulder 16^a, the reduced portion being occupied by a light coiled spring 19, the front end of which 15 bears against the shoulder 16^a and the rear end of which bears against the shoulder 15 of the tenon 9, whereby the locking-bolt is normally forced forward to effect a locking engagement with the barrel and thus retain 20 the latter closed. The rear end of the top locking-bolt projects beyond the receiver and may be fashioned with an enlarged milled head 20, readily adapted to be engaged by the thumb of the user so that the 25 bolt may be withdrawn to disengage it from the barrel and permit the latter to open. The barrel, it will be understood, has its extension 55, hinged in the usual manner, at 21, to the front extension of the receiver or 30 frame, and when released as described from its engagement with the top locking-bolt, the barrel may be opened in the usual manner for the purpose of withdrawing or ejecting the empty shell and reloading the gun.
- 35 Below the bore 12 and in line with the center of the barrel, the receiver or frame is provided in its underside with a longitudinally recess or chamber 22, extending from its rear end to a point near its front, (see Fig. 40 6,) and the top of this recess or chamber communicates with a similarly disposed though narrower recess 23, which in turn, communicates with a longitudinally disposed cylindrical bore 24, the front of which 45 is reduced and pierces the front wall of the receiver or frame, as indicated at 25.
- The bores 24 and 25, are occupied by the firing-pin 26, the front of which is reduced, as at 27 so that the pin and bores correspond 50 in shape and proportions. The rear end of the firing-pin is reduced, as at 28, and terminates in opposite trunnions 62, forming what might be termed a T-head. In advance of this head there is mounted loosely 55 upon the rear reduced portion of the firing-pin a collar 29, between which and the enlarged portion 26 of the pin there is mounted a compressible coiled main-spring 30.
- Pivottally supported upon a transverse pin 60 32, mounted in parts hereinafter described, is a sear 33, the same being located in the narrow recess 23. This sear is provided at its rear upper corner with an angular locking-shoulder 34, which normally engages

with a corresponding notch or recess 31, 65 formed in the underside of the firing-pin 26, such engagement being maintained at all times except when the gun is fired by means of the spring 30 upon the firing-pin. The lower rear corner of the sear is provided 70 with an extension 35, the upper edge of which is preferably inclined, and in advance of said extension the lower edge of the sear is provided with a recess forming a shoulder 36, the functions of the extension and shoulder being hereinafter described.

Closing the bottom of the recess or chamber in the receiver or frame is a cover-plate 37, (see Fig. 4,) the front end of the plate being, in this instance, reduced to form a 80 tenon 38, seated in a corresponding recess 39, formed in the underside of the receiver and in advance of the chamber 22 therein. To secure the front end of the plate in position, the tenon is apertured for a screw 40, 85 which extends through the tenon and into the bottom of the aforesaid recess in the receiver. This screw may also be utilized for retaining the front perforated end of the 90 usual trigger-guard 41, the rear end of the guard removably engaging a suitable kerf 41^a, formed in the underside of the cover-plate 37. The rear end of the cover-plate may be extended a desired distance beyond the recess 7 of the stock and secured to the 95 latter by a screw 42.

The cover-plate 37 is formed with a central longitudinally disposed narrow slot 43, which extends nearly the length of the plate, and in the front end of this slot is pivoted, 100 by means of a transverse pin 44, the cocking-plate 45, the same having its outer edge shaped to approximate the surface of the grip of the stock. A light spring 46, in this instance flat, normally forces the cocking-plate outward, so that, as shown in Fig. 1, the outer edge of the cocking-plate normally extends somewhat beyond the cover-plate 37 in which it is mounted. Various ways may be devised for supporting the spring 46, the 110 manner shown merely being one of such, and in this instance consisting of a short standard 47, formed on the inner side of the plate 37 and straddling the slot in said plate and therefore the cocking-plate. This standard is provided near its upper end with a small slot 48, transversely disposed and of key-hole shape in cross-section. Into this slot is slipped and retained the beaded end 49, of the spring. An inverted stirrup 50, may be 115 formed on the inner side of the bottom cover-plate 37 some distance in rear of the standard 47, and within this stirrup the rear free end of the spring 46 may loosely play. This stirrup constitutes a means for limiting the inward movement of the cocking-plate 45, and also the movement in one direction of the firing-pin operating mechanism 120 125

to be hereinafter described. When the cocking-plate is in its normal or projected position, as in Fig. 1, a shoulder 64, formed at its upper forward end, engages the shouldered recess 36 in the underside of the sear, thereby preventing a depression of the sear and therefore its disengagement with the firing-pin.

The trigger 51, is pivoted upon the pin 44, and at one side is recessed, as at 51^a, (see Fig. 13,) to form a passage for the cocking-plate. Above its point of pivot the trigger is formed with a forwardly disposed curved head 52, the end of which overhangs and rests upon the upper inclined edge or cam-surface of the extension 35 of the sear, whereby, as will be evident, when the trigger is pulled or retracted, the head thereof will serve to depress the rear free end of the sear 33 and thus cause its shoulder 34 to disengage from the notch 31 of the firing-pin, thereby liberating the pin and permitting it to be influenced by the main-spring 30 if the latter be compressed. This operation, however, cannot take place unless the cocking-lever has first been compressed within the receiver so that its shoulder 64 has disengaged from the shouldered recess 36 of the sear.

As shown by dotted lines (Figs. 1, 2 and 3.) the front wall of the receiver at each side of the sear 33, may be provided with a longitudinal aperture 53, such being in line and communicating with shallow cavities 54, formed in the lower extension 55, of the barrel. In each of these apertures is a reciprocal lower locking-bolt 56, and the ends of these two bolts are connected within the recess 7 of the grip by means of a transverse bearing-pin 57.

Pivoted to the inner side of the cocking-plate 45 and near its rear end, as at 58, is the rear end of a curved cocking-link 59, (see Fig. 12.) This cocking-link travels over and is guided by the stirrup 50, the latter serving to retain the link in position, and at its front end said link is reduced and apertured to receive the pin 57. As shown the link is rounded at its forward end and in its movements travels against the inclined hardened

guide-surface 63 of the upper cover-plate 10. A cocking-bar 60, (see Fig. 11,) has its rear end bifurcated, as at 60^a, such bifurcations embracing the reduced forward end of the cocking-link and being apertured to receive the pivot-pin 57 before mentioned. This cocking-bar 60 has its front end upwardly disposed and rounded, as at 62^a, said end being adapted to ride against the guide-surface 65 of the upper cover-plate 10. In rear of its front end the cocking-bar is preferably slotted, as at 61, and through such slot projects the T-head of the firing-pin, the trunnions 62 of the head engaging the opposite edges of the slot in the cocking-bar.

Taking the parts in the positions in which they are illustrated in Fig. 1, and assuming a shell to be within the chamber of the barrel, it will be apparent that the main-spring 30 is under very little tension, (entirely insufficient to project the firing-pin,) and that therefore, the gun is in an absolutely safe condition, and though loaded, cannot possibly be accidentally discharged; and furthermore that such safe condition of the gun does not depend upon any safety device that might become broken and therefore inefficient for the purpose for which it is intended. In other words, the lock-mechanism is inactive and incapable of discharging a shell because of the inactivity of the main-spring.

To bring the parts to the position illustrated in Fig. 2, wherein the gun is in condition to be discharged, it is only necessary to assume the usual position for firing, that is to clasp the stock 6 of the gun with the hand. This clasping of the stock necessarily raises or pushes inward the rear free end of the cocking-lever 45, thus withdrawing its shoulder 64 from its engaging position with the shouldered recess 36 in the underside of the sear 33, liberating the sear and rendering it subject to a subsequent depression by means of the trigger. The cocking-lever, it will be seen, thus performs an additional safety for the gun, inasmuch as even though the main-spring should be, when retracted or expanded, slightly under tension, yet it will be incapable of projecting the firing-pin because of the latter being locked by the sear and the sear in turn locked by the cocking-lever.

As the cocking-lever is thus operated, the cocking-link 59 moves forward, the upper rounded end of the link being guided by and traveling along the inclined guide-surface 63 of the top cover-plate 10. This movement of the cocking-link causes a similar forward movement of the cocking-bar 60, the upper rounded end of which travels forward along the guide-surface 65 of said top cover-plate 10. During the latter movement of the cocking-bar, the firing-bolt being held stationary, the rounded end of the cocking-bar bearing against the movable collar 29, will force the latter forward against the tension of the main-spring 30, thus compressing said main-spring upon and in rear of the firing-pin 26. The movements of the parts as described may, if desired, also simultaneously cause the lower locking-bolts 56 to move forward and engage with the cavities 54 in the extension 55 located at the underside of the barrel, whereby as will be evident, the barrel will be locked at three different points immediately before the discharge of the gun and during all times that the gun is in condition to be discharged.

It now only remains to pull the trigger in order to discharge the gun, and such operation causes the upper curved head 52 of the trigger operating upon the upper inclined edge of the extension 35 of the sear, to depress the sear and thus disengage its shoulder 34 from the notch 31 of the firing-pin 26. Immediately the parts assume the position in which they are illustrated in Fig. 3, and as soon as the cocking-lever is released from the pressure of the hand, the return-spring 46 will return the parts to the original position shown in Fig. 1. In the latter position the lower locking-bolts will have been withdrawn from engagement with the lower extension 55 of the barrel, and to open the latter for the purpose of ejecting or withdrawing the empty shell it is only necessary to draw back the top locking-bolt. The gun may now be reloaded. When the parts are in the act of resuming their normal or inactive position, the inverted stirrup 50, in addition to performing the function of a guide for the cocking-lever and a retainer for the return spring, also serves as a support and stop for the cocking-link 59 and therefore for the parts supported thereby. It will be apparent that in the construction of gun described but comparatively few parts are employed; that such parts may be constructed of sufficient size to render them durable and not likely to become impaired or broken; and furthermore, that the receiver or frame is formed of a solid casting the strength of which remains unimpaired by excessive chambering or recessing. It will also be seen that the top and sides of the chamber are closed and devoid of openings through which moisture could obtain access. By removing the top cover-plate access to the interior of the lock-mechanism is readily obtained, and by removing the two screws 11 and 42, the stock may be removed and the whole internal mechanism exposed to view for repair, cleaning, or replacement of any parts that might be broken.

Having described my invention, what I claim is:

1. In a fire-arm, the combination with a receiver provided at its rear end near its upper side with a recess, of a stock having its forward end recessed to receive the lock-mechanism of the arm and provided in its upper side with an opening giving access to said recess, and a top cover-plate secured removably at its rear end to the stock and provided at its front end with a tenon removably fitting the recess in the end of the receiver.
2. In a fire-arm, the combination with a receiver longitudinally bored near its upper side and in rear of its bore provided with a recess, and a barrel hinged to the receiver and provided with a cavity in line with the

bore of the receiver, of a stock having its forward end recessed to accommodate the lock-mechanism of the arm and open in its upper side, a top cover-plate secured at its rear end to the stock and at its front end provided with a tenon removably engaging the recess in the rear end of the receiver and having its upper side formed with a groove in line with the bore of the receiver, a locking bolt mounted for reciprocation in said groove and bore and adapted at its front end to engage the cavity in the barrel and at its rear end provided with an enlargement, said bolt having a reduced rear portion, and a coiled-spring mounted on said reduced portion of the bolt and abutting against the front end of the tenon of the cover-plate and adapted to normally press the bolt forward for the purpose of engaging with the cavity in the barrel.

3. In a fire-arm, the combination with a receiver having a bore, of a firing-pin mounted to reciprocate in said bore and provided with a reduced rear end, a collar mounted to slide upon the reduced rear end, a main-spring mounted upon said reduced portion in advance of and borne upon by the collar, a cocking-plate pivoted in the underside of the arm and adapted to be elevated within the receiver and to be normally projected therefrom, a cocking-bar loosely engaging the rear end of the firing-pin and adapted to bear against the collar thereon, a link pivotally connected to the opposite end of the cocking-bar and having its rear end pivotally connected to said cocking-plate, a trigger, and means operated by the trigger and normally engaging and locking the firing-pin.

4. In a fire-arm, the combination with a receiver having a bore, of a firing-pin mounted to reciprocate in said bore and provided with a reduced rear end having a T-head, a collar mounted to slide upon the reduced rear end, a main-spring mounted upon said reduced portion in advance of and borne upon by the collar, a cocking-plate pivoted in the underside of the arm and adapted to be elevated within the receiver and to be normally projected therefrom, a cocking-bar slotted at its front end to engage the reduced portion and head of the firing-pin and adapted to bear against the collar thereon, a link pivotally connected to the opposite end of the cocking-bar and at its opposite end pivotally connected to said cocking-plate, a trigger, means operated by the trigger and normally engaging and locking the firing-pin, and a spring for normally pressing the cocking-plate without the receiver.

5. In a fire-arm, the combination with a receiver having a bore, of a firing-pin mounted to reciprocate in said bore and provided with a rear reduced end, a collar mounted

to slide upon said reduced end, a main-spring mounted on said end in advance of the collar and borne upon thereby, a cocking-plate pivoted in the underside of the arm and adapted to be elevated within the receiver and to be normally projected therefrom, a cocking-bar slidably connected at its upper end to the rear reduced end of the firing-pin and adapted to bear against the collar thereon, a link pivotally connected to the opposite end of the cocking-bar and having its opposite end pivotally connected to the said cocking-plate, a spring for normally pressing the cocking-plate without the receiver, a sear pivoted in the receiver and having a shoulder in normal engagement with a recess in the firing-pin, and a trigger pivoted in the receiver and operatively connected with the sear and adapted to depress the same and disengage it from the firing-pin.

6. In a fire-arm, the combination with a receiver having a bore, of a firing-pin mounted for reciprocation in said bore, a main-spring in rear of the firing-pin, a cocking-plate pivoted in the underside of the receiver, means for normally projecting said plate without the receiver, mechanism operated by a compression of the cocking-plate for compressing the main-spring of the firing-pin, a trigger, and an element for normally locking said firing-pin in its retracted position and adapted to be operated by said trigger.

7. In a fire-arm, the combination with a receiver having a bore, of a firing-pin mounted to reciprocate therein, a main-spring in rear of the firing-pin, a cocking-plate pivoted in the underside of the receiver, means for normally projecting the plate without the receiver, means operated by the cocking-plate when the latter is compressed to compress said main-spring, a sear pivoted in the receiver and having a shoulder for normally engaging and locking the firing-pin in its retracted position and having a rearward extension provided with an inclined edge, and a trigger pivoted in the receiver and at its upper end having a curved head engaging and adapted to ride upon the extension of the sear and depress the same to disengage it from the firing-pin.

8. In a fire-arm, the combination with a receiver having a bore, of a firing-pin mounted to reciprocate therein, a main-spring in rear of the firing-pin, a cocking-plate pivoted in the underside of the receiver, means operated by the cocking-plate when the latter is compressed to compress said main-spring, means for normally projecting said cocking-plate from the receiver, a sear pivoted in the receiver and normally engaging and locking the firing-pin in its retracted position, and a trigger pivoted in the re-

ceiver and having its upper end operatively engaged and adapted to depress the sear and disengage the latter from the firing-pin.

9. In a fire-arm, the combination with a receiver having a guide, of a firing-pin located and adapted to reciprocate therein, a sear pivoted in the receiver and normally engaging and locking the firing-pin and provided on its underside with a shoulder, a trigger pivoted in the receiver and adapted to depress the sear so as to disengage it from the firing-pin, a main-spring for projecting the firing-pin, a cocking-plate pivoted in the underside of the receiver and having a shoulder at its front end beyond its pivot for engaging the shoulder on the underside of the sear, means for normally projecting the rear end of the cocking-plate without the receiver, and means operated by the compression of the cocking-plate for compressing the main-spring of the firing-pin.

10. In a fire-arm, the combination with a receiver having a guide, a firing-pin mounted to reciprocate therein, a spring for projecting the firing-pin, a cocking-plate pivoted in the underside of the receiver, means for normally projecting the cocking-plate without the receiver, and means connected to the cocking-plate and operated thereby for placing the spring under tension when the cocking-plate is retracted, of a trigger pivoted in the receiver, and a locking device for the firing-pin adapted to be operated by the trigger.

11. In a fire-arm, the combination with a receiver having its underside chambered, the upper side of which is provided with a narrow slot, said chamber and slot terminating short of the front of the receiver, and a bore through the receiver immediately above and communicating with said slot, of a reciprocating firing-pin having a notch and a reduced rear end terminating in a head, a sliding collar mounted on said reduced end, a coiled spring also mounted on said reduced rear end in advance of the collar, a cocking-plate pivoted in the under side of said chamber, means for normally projecting said plate beyond the chamber, a slotted cocking-bar engaging loosely the rear head of the firing-pin, a link pivoted to the rear end of the cocking-bar and to the cocking-plate, a sear pivoted at its front end in the slot of the receiver and at its rear upper end having a shoulder for engaging the notch in the firing-pin and thereby locking the same against forward movement, and a trigger pivoted in the chamber and above its pivot operatively connected with and adapted when pulled to depress and disengage the sear from the firing-pin.

12. In a fire-arm, the combination with a receiver having a longitudinal bore and be-

low the same a communicating chamber, a stock recessed at its front end and connected to the receiver, and a cover-plate connected to the receiver and stock and closing the upper side of the recess in the latter, said cover-plate being provided with the angularly related guide-surfaces 63 and 65, of a firing-pin having a reduced rear end terminating in a head and mounted in the bore 10 of the receiver, a spring mounted on the reduced portion of the firing-pin, a cocking-plate pivoted in the chamber, means for normally projecting the plate without the chamber, a link pivoted at its rear end to the rear end of the cocking-plate and having its upper front end adapted to contact with the rearmost of the aforesaid guide-surfaces of the cover-plate, a cocking-bar loosely connected to said link and adapted to be operated thereby and having its front portion slotted and loosely engaging the rear reduced portion of the firing-pin and above said point adapted to contact with the foremost of said guide-surfaces of the top cover-plate, a trigger pivoted in the bottom of the chamber of the receiver, and a sear pivoted between the firing-pin and trigger and within the receiver, said sear having a shoulder for engaging the firing-pin and being adapted to be depressed when said trigger is pulled.

13. In a fire-arm, the combination with a receiver having a bore and below the same a chamber, and a stock connected to the receiver and recessed in line with the chamber of the receiver, of a firing-pin mounted to reciprocate in the bore of the receiver and having a rearwardly disposed reduced portion terminating in a head, a slotted bottom cover-plate closing the lower side of the chamber of the receiver and the recess of the stock, an inverted stirrup mounted on said cover-plate, a standard mounted on said cover-plate in advance of the stirrup, a cocking-plate pivoted in the slot of said cover-plate and embraced by the stirrup, a flat spring secured at its front end to the standard and extending under the stirrup and at its free end bearing on the inner side 50 of the cocking-plate and adapted to normally project the latter without the slot of the bottom cover-plate, a trigger pivoted in the slot of the cover-plate, a sear pivoted in the chamber of the receiver, said sear being operatively connected with the trigger and adapted when elevated to lock the firing-pin, a cocking-bar loosely engaging the head of the firing-pin and adapted to slide over the reduced portion of said pin, a main-spring 55 mounted on said reduced portion of the firing-pin in advance of and adapted to be compressed by the cocking-bar, and a link pivoted to the rear end of the cocking-bar and at its rear end pivoted to the rear

end of the cocking-plate and adapted when lowered to rest upon the stirrup heretofore mentioned.

14. In a fire-arm, the combination with a receiver and a barrel pivoted in front of the same, said barrel having a lower extension 70 provided with a cavity, and the receiver having a bore in line with the barrel and below the same provided with a passage communicating with said cavity, of a firing-pin mounted to reciprocate in the bore of the receiver, a cocking-plate pivoted in the bottom of the receiver and normally projected without the same, a spring for projecting the firing-pin, means operated by the cocking-plate when compressed to place said spring under tension, and a locking-bolt located in the passage of the receiver and adapted to engage the cavity in the extension of the barrel and adapted to be projected by the means employed for placing the spring under tension.

15. In a fire-arm, the combination with a receiver chambered in its underside and above the same having a bore, and a barrel hinged to the receiver and provided with a bottom extension provided with apertures, said receiver having opposite passages communicating with said apertures, of a firing-pin mounted to reciprocate in the bore of the receiver, a coiled main-spring in rear of said pin, a cocking-plate pivoted in the receiver, means for normally projecting the plate without the chamber, a cocking-link pivoted at its rear end to the cocking-plate, a cocking-bar in rear of the firing-pin, connected thereto and adapted to compress the coiled-spring and at its rear end pivoted to the forward end of the cocking-link, opposite locking-bolts loosely connected at their rear ends to the joint between the cocking-bar and the cocking-link and having their front portions located in the passages of the receiver, whereby when said cocking-plate is compressed said bolts are advanced to engage in the apertures of the extension of the barrel, a sear pivoted in the receiver between said bolts and adapted to engage the firing-pin when the latter is retracted by the cocking-bar, and a trigger pivoted in the chamber of the receiver and operatively connected with the sear and adapted to depress the same from its engagement with the firing-pin.

16. In a fire-arm, the combination with a receiver having a chamber in its underside, a stock recessed in line with the chamber and connected to the receiver, a barrel hinged to the receiver and provided with a bottom extension having an aperture in line with a passage formed in the front wall of the receiver, of a cover-plate for closing the bottom of the chamber of the receiver and the recess of the stock, said cover-plate having

a slot, an inverted stirrup rising from the cover-plate, a plate pivoted in the slot of the cover-plate below the stirrup, a spring for normally projecting said plate without 5 the slot, a link pivoted to the plate and limited in its movements by the stirrup, and a locking-bolt pivoted at its rear end to said link and having its front portion located in

the passage of the receiver and when advanced adapted to engage the aperture in 10 the extension of the barrel.

In testimony whereof I have signed my name to this specification in the presence of two subscribing witnesses.

ALLAN W. WOODRUFF.

Copies of this patent may be obtained for five cents each, by addressing the "Commissioner of Patents, Washington, D. C."
